UNITED STATES PATENT OFFICE.

JAMES W. KNIGHTS, OF HAMMERSMITH, LONDON, ENGLAND.

COIN-FREED GRAMOPHONE.

1,262,521.

Specification of Letters Patent.

Patented Apr. 9, 1918.

Application filed February 18, 1915, Serial No. 9,131. Renewed February 19, 1918. Serial No. 218,173.

To all whom it may concern:

Be it known that I, JAMES WILLIAM KNIGHTS, a subject of His Majesty the King of England, residing at Hammersmith, in the county of London, Kingdom of England, have invented certain new and useful Improvements in or Relating to Coin-Freed Gramophones, of which the following is a specification.

10 This invention relates to improvements in coin-freed gramophones of the kind in which a plurality of gramophone records and tone arms are so arranged that any desired record of the plurality of records can be reproduced on the operation of the coin-freed mechanism.

The present invention consists in the improved construction, arrangement and combination of parts hereinafter described and 20 more particularly pointed out in the appended claims.

I will now describe my invention with reference to the accompanying drawings in which:—

25 Figure 1 is a diagrammatic side elevation of part of one form of my improved coin-freed gramophone.

Fig. 2 is an enlarged sectional side elevation of the opposite side;

30 Fig. 3 is a part plan;

Fig. 4 is a part front sectional elevation; and

Fig. 5 is a front elevation of a modification.

35 As shown I provide a plurality of turn tables *a* on which are disposed gramophone records or disks *a'*. These tables are mounted in any convenient manner on a central spindle or shaft *b* rotatably mounted in 40 brackets or the like *c* projecting from a suitable casing or the like *d*. Above each table or record is disposed a movable tone arm *e*, fitted with any usual sound box *f* which is adapted to rest, when lowered, on the de-

45 sired record, so that sound will be transmitted therefrom to a common sound tube *g* mounted on the casing *d*, and provided at its upper end with any usual amplifying means or horn *h*. These tone arms *e* are

50 adapted to be raised and lowered by any suitable means such as cams or elliptical carriers *i* which are mounted transversely of the tone arms in brackets *j* attached to the brackets *c*. As shown in Fig. 1 these

55 cams are adapted to be separately rotated by means of bell-crank levers *k* which are oper-

ated in any well known manner by coin-freed mechanism not shown. Such mechanism could conveniently comprise a plurality of cams on a common shaft against 60 which rollers on the ends of the levers *k* might be separately brought into position. The cams *i* are also connected at their opposite ends to bell-cranks *l* which are adapted to operate baffle plates *m* in the sound tube 65 so that only the particular tone arm, that has been lowered, is put into communication with the sound tube as shown in section in Fig. 2. In order to bring the tone arms back to the commencement of the record, I may 70 provide adjustable arms *n* arranged with antifriction rollers in such a manner that on the rotation of the spindle *o*, by hand or automatically after each operation, the outer ends of the arms *n* will push the tone 75 arms to the inner part of the disk or commencement of the record. Suitable adjustable stops *p* may be provided to limit the movement of the tone arms when required such as when a short record is used. 80

In operation and when a coin is inserted in the coin-freed mechanism, the spindle *b* is rotated and also the plurality of records *a'* and at the same time one of the tone arms *e* is lowered onto the record corresponding 85 to the selected tune. This tone arm *e* may be actuated by an external index finger adapted to point on an index of the various tune selections or the like through the medium of the corresponding bell-crank lever 90 *k* and cam *i* which is rotated to the position shown in the lower part of Fig. 1. During this movement of the cam *i* the bell-crank lever *l* on the opposite side is actuated thus moving the baffle plate *m* and putting the 95 tone arm into communication with the sound tube for the reproduction of the desired record.

In a modification as shown in Fig. 5, I control the cams *i* by means of sectors *q* 100 on the cam shaft. These sectors are actuated by worms *r* through the medium of bevel wheels *s*, shafts *t* and bevel wheels *u*, on the lower ends of the said shafts *t*, which engage with bevel wheels *u'* loosely mounted on a shaft *w*. On each of the bevel wheels *u'* I provide a spur wheel *v* and these spur wheels are adapted to be separately engaged by a common spur wheel *y* 110 slideable upon a square driven shaft *x* and controlled by the operator. Thus the operation of any one of the spur wheels *v*

will serve to lower its respective tone arm and put the machine into operation for playing the selected tune or piece.

Although I have shown rods and bell 5 crank levers for transmitting the power, I might conveniently substitute Bowden wire for this purpose.

What I claim as new and desire to secure by Letters Patent in the United States is:—

- 10 1. A coin-freeed gramophone comprising a plurality of rotatable tables to receive records, a common sound tube, a plurality of tone arms mounted on the tube, each tone arm adapted to operate on a separate record, a plurality of cams, one cam located beneath each tone arm to raise and support the same, a plurality of baffle plates mounted in the sound tube for controlling communication between the sound tube and tone arms, and a connection between each cam and baffle plate of the desired tone arm to open the baffle plate upon the turning down of the cam to lower the said tone arm.
- 20 2. A coin-freeed gramophone comprising a plurality of rotatable tables for supporting records one above the other, a vertical sound tube having a plurality of openings throughout its length, a plurality of tone arms mounted on and supported by the sound tube and in communication with the sound tube, each tone arm being adapted to operate on a separate record, a plurality of cams for normally maintaining the tone arms out of contact with the records, baffle plates 30 for closing the communication between the tone arms and sound tube, each baffle plate being connected to a cam, and means for independently actuating each cam whereby upon the actuation of a cam for lowering the tone arm the baffle plate of the respective tone arm will be operated for forming a communication between the tone arm and sound tube.
- 40 3. A coin-freeed gramophone comprising a plurality of rotatable tables on which records are mounted, a common sound tube, and tone arms normally in communication therewith, means for cutting off communication between each tone arm and the sound tube, means for raising and lowering the tone arms from and to the tables, and connecting devices between the raising and lowering means and the cut-off means for causing the latter to be operated by the former.
- 50 4. A coin-freeed gramophone comprising a plurality of horizontal rotatable tables ar-

ranged one above another and each adapted to support a record; a common sound tube; a plurality of tone arms, one for each of said records, mounted on said sound tube; a plurality of devices, one for each of the tone arms, adapted to be separately operated to raise and lower their respective tone arms; a plurality of baffle plates, one for each of the tone arms, mounted within the sound tube; and operative connections between said raising and lowering devices and said baffle plates.

5. A coin-freeed gramophone comprising a plurality of horizontal rotatable tables arranged one above another and each adapted to support a record; a common sound tube; a plurality of tone arms, one for each of said records, mounted on said sound tube, and adapted to be separately brought into engagement with the respective records to reproduce the same; rotatable arms to return each of said tone arms into its starting position when the reproduction of the respective record is finished; and adjustable stops to limit the movement of the tone arms.

6. A device as specified comprising a common sound tube, a vertically arranged rotary spindle spaced from the tube, a plurality of horizontal vertically spaced apart tables mounted on the spindle to rotate therewith and support a series of independent records, a series of tone arms projecting from said common tube into position over the respective records, means for normally holding all of the tone arms out of contact with the records, and means for releasing the tone arms as selected for engagement with the records.

7. In a device as specified, a sound tube, a plurality of rotary tables, a tone arm for each table adapted to communicate with the sound tube, supports for normally holding the tone arms out of contact with the tables and out of communication with the sound tube, and means for releasing the selected tone arm to engage the table and to communicate with the sound tube.

In testimony whereof I have hereunto signed this specification in the presence of two subscribing witnesses.

JAMES W. KNIGHTS.
